UNITED STATES PATENT OFFICE.

WALTER S. STEVENSON, OF PHILADELPHIA, PENNSYLVANIA, ASSIGNOR TO
THOMAS, ROBERTS, STEVENSON & CO., OF SAME PLACE.

DESIGN FOR A COOKING-STOVE.

Specification forming part of Design No. 6,737, dated July 1, 1873; application filed June 4, 1873.

To all whom it may concern:

Be it known that I, WALTER S. STEVENSON, of the city of Philadelphia, in the State of Pennsylvania, have invented a certain Design for a Cooking-Stove, of which the following is a specification:

The nature of my design is fully represented in the accompanying engraving, to which reference is made.

The edge-moldings a' and b' of the two top plates A and B, respectively, are slightly-curved bevels extending downward and outward, as plain surfaces, from the plain flat surfaces of the said plates A B, respectively. The edge-moldings c' and d' of the door C and the panel D, respectively, are plain, slightly-curved bevels, in relation to the faces, respectively, of the same. The faces are flat, with the exception of a block-molding, f , in bas-relief, around between the said faces and their edge-moldings, respectively, and a bas-relief ornamental center piece in each. The center piece on C is surrounded by a bas-relief oval ring having a rope molding, 2, within it, as shown. The center piece on D is also surrounded by a bas-relief oval ring like that on C, but has not the rope molding shown in the latter. The front plate F of the oven has a flat face inclosed by a block-molding border, f' , a bas-relief ornamental center piece, g' , and oval ring and rope bead 2, as shown on the door C. The right and left ends of this plate F have each a rounded pilaster, 3 3, with a bas-relief ornament, 4, in its middle. The fire-doors E E have each a flat face, e' , a bas-relief center piece, g'' , a block-molding border, f'' , and bevel-edge molding e'' , substantially the same as shown on the panel D. The front

plate H of the fire-chamber projects forward at its upper part, which is grooved on its under side, as shown at h' , and its right and left sides or ends are rounded and ornamented, as shown at 5 5. Each of the front legs I I' is of the ornamented form on the face side or front, as shown in I. Each of the rear legs J J' is of the ornamented form on the face side or front, as shown in J.

I claim, as my invention, the design for a stove, consisting of the following particulars, viz:—

1. In combination with the bevel-edge moldings $c' d' e'$ of the doors and panels C D E, respectively, the block-molding border $f' f''$ and flat faces thereof, substantially as shown.
2. In combination with the front plate F, the block-molding border f' , rounded right and left ends 3 3, and the ornamental bas-relief figures 4 4 thereon, substantially as shown.
3. The bas-relief central ornamental figures $g' 2 g' 2$ on the door C and plate F, respectively as shown.
4. The bas-relief central ornamental figures $g'' g''$ on the panel D and fire-doors E, respectively as shown.
5. The ornamented projection h' of the plate H and the rounded ends 5 5 thereof, substantially as shown.
6. The ornamental face of the front legs I I', as shown.
7. The ornamental face of the rear legs J J', as shown.

WALTER S. STEVENSON.
